UNITED STATES PATENT OFFICE

CLARENCE H. MORROW, OF CLEVELAND, OHIO, ASSIGNOR TO THE HOTSTREAM HEATER COMPANY, OF CLEVELAND, OHIO, A CORPORATION OF OHIO

HOT WATER HEATER

Application filed May 27, 1929. Serial No. 366,377.

This invention relates to hot water heaters, its object being to provide a very simple and inexpensive heater designed for convenient attachment to a receptacle for heating or maintaining the temperature of the water or other liquid therein.

Further objects of the invention are in part obvious and in part will appear more in detail hereinafter.

In the drawings, which represent one embodiment of the invention, Fig. 1 is a sectional elevation illustrating the heater attached to a receptacle; Fig. 2 is a sectional elevation on approximately the line 2—2, Fig. 1; and Fig. 3 is a sectional plan view on the line 3—3, Fig. 2.

Experience has shown that it is frequently desirable to provide certain kinds of receptacles or containers for holding liquid with means for heating the liquid therein or for maintaining its temperature. One such instance, referred to for convenience and not in any sense of limitation, is the modern domestic washing machine, which frequently comprises a tub or container for the liquid made, let us say, of sheet copper or the like, with the desirability on the part of the housewife to maintain the water hot in the tub during the washing operation while the agitator is moving the clothes through the soapy water or other detergent. The present invention supplies a domestic heater which can be readily attached to such a washing machine tub or other container and nevertheless is very inexpensive, quite simple to operate and exceedingly durable and rigid in its construction.

In the drawings 1 represents more or less conventionally a portion of a washing machine tub, which may be assumed to be of relatively thin sheet metal. The heater includes as an essential element a coil or other member for circulating the water to a heating medium, such as a flame, and, as is usual, said member must communicate with the container at two different levels to provide a thermal circulation system. The present heater therefore comprises a suitable water circulating member, such as the copper coil 2, consisting of a copper pipe wound in spiral

form with its ends terminating in threaded members 3 to which simple threaded sleeves 4 are connected. The sleeves may be simply threaded into the members 3 or brazed, soldered or otherwise secured thereto in such manner as to avoid the production of leaks upon rise in temperature. Upon said fittings 4 are threaded inner and outer nuts 5, 6. The attachment of the heater to the tub 1 is effected by cutting, boring or otherwise producing the two necessary openings through which the fittings 4 are inserted, and the nuts 5 are drawn up tight on opposite sides to compress the sealing washers or gaskets 7 against the wall of the tank and effect a tight seal or joint.

Associated with the coil is a suitable casing or jacket and means for supporting a burner or heater so as to produce a chimney effect and carry the heated products of combustion or flames past the coil. Furthermore, the heater is sustained by the tub and not from a separate support, due to the fact that the washing machine is usually moved from place to place, so that the present heater is designed with its own stiffening member or backbone, which also serves in the present heater to prevent rotation of the members 3 in the act of attaching the heater to the tub, and thereby preventing injury to the coil by the fastening operation.

The casing or jacket of the present heater includes a backbone or spine member 8, Fig. 2, which may be of any suitable form for the purpose, but is shown as a cast metal member having its rear surface curved in cylindrical form and provided with upper and lower openings 9 through which the members 3 extend. The wall or member 8 around said openings is preferably more or less flat, as at 10, Fig. 3, to form a seat for shoulders at the ends of members 3, so that the latter can be clamped to the spine or backbone by the clamping nuts 11. Also, member 8 is provided with longitudinal ribs 12 which are more or less straight and lie directly opposite the straight side walls 13 of members 3 and form stops or abutments to prevent rotation of said members when the nuts 11, 5 and 6 are

turned up either in assembling the heater itself or in attaching it to the tub.

The entire coil is surrounded by a casing or jacket 14, which may be of suitable thin metal, preferably of two plies with a layer 15 of heat insulating material such as asbestos therebetween, and provided with an open bottom and top, the latter being closed when desired by a detachable cover 16 having a knob 17. This sheet metal jacket has openings through which the fittings 4 extend and it is clamped firmly in position and supported by said fittings between the spine or backbone 8 and the clamping nuts 11 before referred to. 15 The jacket may also be provided with lower and upper openings 18, 19 for air and gas circulation.

The lower end of the spine or backbone 8 is provided with a forwardly extending bracket portion 20 reinforced by a rib 21 and pierced at its forward end at approximately the central axis of the heater to receive a bolt 22 for clamping a suitable heater in position beneath the coil, such as the gas burner 23 of ordinary form, provided with a Bunsen mixer 24 and a valved gas connection 25. The bolt 22 may be loosened and the burner turned around the central axis to lead its gas supply to it from any desired direction.

30 In use of the device where there is no danger from gas fumes the cover 16 may be applied and air enters the bottom of the casing around the burner and through the openings 18 and passes out to the open atmosphere 35 through the openings 19. However, if desired, the cover 16 may be removed and proper sections of stove pipe or other conduit fitted to the top of the casing to conduct the fumes to a stack. 26 indicates a suitable baffle of 40 generally disc-like form provided with projections and otherwise suitably formed to nest and lie snugly on top of the upper turn of the spiral, to which it may be wired if necessary. This baffle compels the heated products of combustion to pass outwardly between 45 the turns of the spiral rather than directly through the open top of the coil.

This heater is of very simple form but possesses all the attributes and requirements 50 of the more expensive domestic hot water heaters designed for storage tanks. At very small cost it includes a quite rigid structure which may be readily attached to a thin walled tank for maintaining the temperature 55 of the water therein. Other advantages will be apparent to those skilled in the art.

What I claim is:

1. A water heater especially adapted for use with a water containing device having a 60 relatively light sheet metal wall on which said heater is adapted to be mounted, comprising a water circulating member having one-piece terminal members secured on the two ends thereof, each of said terminal members having a threaded end portion adapted to extend

through an opening in the supporting wall of said device and to receive a securing nut, whereby said circulating member can be mounted on said wall of said device, a relatively light sheet metal casing enclosing said circulating member and provided with a pair of openings through which said terminal members extend, and a relatively heavy bar-like member extending vertically along the inner surface of said casing and provided with a pair of openings registering with the openings of said casing and through which extend the terminal members of said water circulating member, said bar-like member providing a sturdy and rigid support for said terminal members in said casing. 70 75 80

2. A water heater especially adapted for use with a water containing device having a relatively light sheet metal wall on which said heater is mounted, comprising a water 85 circulating member having terminal members provided with threaded portions adapted to extend through openings in the supporting wall of said device and carrying clamping nuts, a rigid device connecting said terminal members, a casing enclosing said device and said circulating member and having openings through which the threaded portions of said terminal members extend, said rigid device being provided at its lower end with a bracket 90 and a burner mounted on said bracket and rotatably adjustable about the central axis of said water circulating member. 95

In testimony whereof I hereby affix my signature.

CLARENCE H. MORROW.
